UNITED STATES PATENT OFFICE.

FRANK G. NOVY, OF CLEVELAND, OHIO.

DESIGN FOR A VEHICLE-SIGNAL.

48,251.

Specification for Design.

Patented Dec. 7, 1915.

Application filed June 17, 1915. Serial No. 34,748. Term of patent 7 years.

To all whom it may concern:

Be it known that I, FRANK G. Novy, a citizen of the United States, residing at Cleveland, in the county of Cuyahoga and State of Ohio, have invented a new, original, and ornamental Design for a Vehicle-Signal, of which the following is a specification, reference being had to the accompanying drawings, forming part thereof.

In the drawings, Figure 1 is a front view

of a vehicle signal of my design, Fig. 2 is a side view of the same, and Fig. 3 is a perspective view, looking toward the rear side thereof.

I claim:

The ornamental design for a vehicle signal, as shown.

In testimony whereof I affix my signature.

FRANK G. NOVY.
